UNITED STATES PATENT OFFICE.

MICHAEL F. HAYES, OF BOSTON, MASSACHUSETTS.

AUTOMATIC SELF-CONTAINED FIRE EXTINGUISHER.

Application filed July 8, 1921. Serial No. 483,309.

To all whom it may concern:

Be it known that I, MICHAEL F. HAYES, a citizen of the United States, residing at Boston, in the county of Suffolk and State 5 of Massachusetts, have invented an Improvement in Automatic Self-Contained Fire Extinguishers, of which the following is a specification.

This invention relates to automatic, self-contained fire extinguishers which are especially adapted to be installed in buildings, as moving picture booths, garages, warehouses, and the like to serve the purpose and take the place of a complicated and 15 expensive automatic sprinkler system.

An object of my invention is to improve the construction and operation of automatic, self-contained fire extinguishers.

The device embodying my invention includes a container for the fire-extinguishing fluid, means to generate a gaseous pressure within the container to cause the forcible ejection of the fluid therein, and temperature-responsive means to govern the 20 generation of pressure. I preferably employ a solution of water and bi-carbonate of soda in the container and means controlled by the temperature-responsive means to mix an acid, as sulphuric acid, into the solution 25 in the container whereby to build up a gaseous pressure in a well-known manner to act upon and forcibly eject the solution.

The container is provided with means whereby it may be secured removably to a 30 wall or ceiling or other support in the room it is designed to protect from fire. When the device is to be installed in a cold or non-heated room, as an isolated or detached garage and the like, I provide means to keep 35 the solution in the container from freezing; and the means may comprise an outer shell enclosing and spaced from the container to provide a temperature-insulating, dead-air space about the container; and this 40 constitutes a further object of the invention.

It is a yet further object of the invention to provide manually-operable stirring means disposed within the container having manually-engageable means on the outside thereof adapted to be manipulated at intervals to prevent the collection of a deposit of bi-carbonate of soda at the bottom of the container.

55 A further object of my invention is to provide a rotatable discharge or spraying

device actuated by pressure or motion of the fluid passing through it to spray and distribute jets of fire extinguishing fluid to objects within its range.

Fig. 1 is a front elevation of an automatic, self-contained fire extinguisher embodying my invention.

Fig. 2 is a vertical section through the device of Fig. 1.

Fig. 3 is an enlarged detail of the acid-holding means and thermostatic acid-release means.

Fig. 4 is a plan detail of Fig. 3.

Fig. 5 is a plan detail of the acid bottle holder.

Fig. 6 is a section along line 6—6 of Fig. 2.

Fig. 7 is a section along line 7—7 of Fig. 2 with the acid-holding and thermostatic control means removed and illustrating more particularly the scraper.

Fig. 8 is a section along line 8—8 of Fig. 2 and illustrating a section of the rotatable spraying device.

Fig. 9 is a modified form of the invention wherein the outer and temperature insulating tank is omitted.

Fig. 10 is a view similar to Fig. 8 but with the bottle holder displaced in the release means for re-filling the bottle.

As here shown the extinguisher embodying my invention may be suspended from a support by the chains 15 and hooks 16 or other suitable attaching-means by which it is removably supported. The extinguisher includes the container 17 for the fire-extinguishing fluid; and said container may be of any suitable shape and as here shown is semi-spherical in form.

A plate 18 comprising a cover for the container is secured on the top thereof by suitable means, as rivets and brazing, to form a pressure tight joint. Said plate is herein shown as flat but obviously may be concave or otherwise shaped whereby the better to resist internal pressure within the container.

A shell 19 preferably encloses and is spaced from the container to provide a dead-air space 20 between the shell and container by which the fire-extinguishing fluid in the container may be protected from a freezing temperature.

If desired, the container may be further protected by packing any well-known heat-insulating medium in the air space, although this packing is not here shown.

Spacing members 21 are secured to the inner face of said

60

shell 19 and serve to locate the container and shell substantially concentrically. A cover 22 is secured removably to said shell and is spaced from the cover of said container.

5 The acid-holding means and release-means and thermostatic control are removable from the container as a unit. Said cover 18 of the container is provided with the internally-screw-threaded neck 23 having the inwardly-directed annular flange 24 in the lower portion of the neck which forms a seat for the acid-holding means, and the aperture 25 through which the fire-extinguishing fluid and the acid-holding means is introduced into the container 17.

10 The acid-holding means and release-means and thermostatic control are carried by the plug 26 which has the exteriorly-threaded end-portion 27 adapted removably to be threaded into the neck of the container; and two projections 28 having recesses which provide means by which the plug may be engaged by a spanner-wrench and rotated.

15 The acid-holding means comprises the ring 29 having the three spaced downwardly-extended integral arms 31 and the plate 32 secured to and between said arms intermediate the ends thereof and upon which the acid bottle 33 is adapted to rest. The acid bottle preferably is made of glass and is supported in an inverted position in said holder. The ends of said arms 31 terminate in the exteriorly-threaded ring 34 in which the upper end of the acid bottle is disposed. An 20 35 interiorly-threaded cap 35 is threaded on said ring and serves to hold the bottle in the holder, and the bottle may be removed for replacements, cleaning and the like by first removing said cap. Preferably a resilient ring 36 of rubber or equivalent, is disposed between the bottle and the cap whereby 25 40 yieldingly to hold the bottle in place.

Said holder is extended in inverted position into the container with the ring 29 thereof resting upon the flange 24 in the neck of the container, and said ring is engaged and held solidly in position by the threaded portion 27 of the plug 26. The open neck 33^a of the acid bottle is normally 30 35 closed by the stopper 37 which preferably is of glass; and the stopper and the neck of the bottle are preferably so tapered that the stopper can easily be removed from the neck by a direct downward pull and yet tightly 40 45 close the bottle against undesired escape of acid. Said stopper is carried by the acid-release means which is under the control of the thermostatic or temperature-responsive means.

50 55 60 65 60 The acid-release means includes the rod 38 having the two forks or branches 38^a and 38^b. Said branches extend downwardly into the container beneath the plug 26 and within the ring 29 of the holder; and the end portions thereof are reduced in size and exteriorly

screw-threaded. The stopper 37 is secured to, as by being embedded in, the bar 39; and said bar is secured removably on the threaded ends of said branches 38^a and 38^b by the nuts 40. Normally said bar is maintained in raised position and the acid bottle is thereby sealed but, upon sufficient elevation of circumambient temperature, the bar is adapted to be moved forcibly downward to withdraw the stopper from the bottle and permit the contents to escape into the container 17 and mix with the bicarbonate of soda solution therein and generate a gaseous pressure.

70 75 80 85 90 95 The rod 38 of the acid-release means is guided for vertical movement in an aperture 41 in said plug and said rod is preferably a close fit therein to reduce gas leakage from the container 17 although other means are provided to seal the aperture when the device is in operation. A supporting bracket 42 is secured to and extends above said plug and has an aperture in the upper end thereof in which the upper end of said rod 38 is slidably received and supported. A compression spring 43 encircles said rod 38 beneath said standard 42 and serves to press said rod downward and extract the stopper from the acid bottle when released by the thermostatic device. A collar 44 is fixed to said rod 38 against which the lower end of said spring presses; and said collar is adapted to rest upon the plug 26 over and seal the aperture 41 therein when the device is in operation.

100 105 110 115 120 The rod 38 of the release means is normally held in raised position against the pressure of said spring 43 by the thermostatic device, as the fusible link 45, which is removably secured on a hook 46 of the standard 42 and a hook 47 of the collar 44 of the acid-release means. It is obvious that, when the temperature of the link 45 is sufficiently high it will separate and permit the spring to force the bar 38 downward to withdraw the stopper from the acid bottle.

125 130 135 It will be noted that the holder for the acid bottle can be moved laterally with respect to the release-means and the stopper 37, to assume a position indicated in Fig. 11, in which position the bottle may easily be re-filled.

The fire-extinguishing fluid may be discharged from the container through any suitable means but I prefer to employ a rotatable device by which the fluid is sprayed over adjacent objects in a very effective manner. Fluid is conducted to the rotatable device through the pipe 50 which extends upwardly from within the container 17 to a point above the fluid level therein and outwardly through a sealed aperture therein and downwardly along and secured to the outer face of the container and within the shell 19. The fluid in the container is normally at atmospheric pressure and the

pipe or conduit 50 must have a portion thereof elevated above the fluid level, or otherwise fluid will escape through the pipe, as said pipe is open at both ends. The 5 lower end of said pipe terminates in the externally-threaded nipple 51 which extends through an aperture in the bottom of said shell 19. A bearing-member having the internally-threaded upper end portion 10 52 is threaded on said nipple. Said bearing-member has the shoulder 53 which forms a seat upon which the rotatable device rotates, and has the hollow tubular extension 54 formed with slots 55 therein through 15 which the fire-extinguishing fluid is discharged from the container.

The rotatable spraying device comprises the hollow ball 56 formed in two complementary threaded half-portions and having 20 a plurality of orifices 57 through the side wall thereof. Said orifices are drilled or otherwise formed in the side wall at an angle with the vertical axis of the ball whereby the reaction of the fluid discharged 25 through the orifices will rotate said ball and cause the jets to drench surrounding objects within range. The upper portion of said ball has an aperture therein which is rotatably received on the upper portion 52 30 of the bearing member and the ball is rotatably supported in position upon the shoulder 53 which engages the inner face thereof.

A screw 58 is adjustably supported in 35 said bearing-member along its axis and the lower portion of said ball is rotatably supported thereon. A collar 59 disposed on the upper portion 52 of said bearing member may serve to restrain the ball against 40 upward axial movement.

A scraper 60 shaped to conform with the interior bottom faces of the container 17 is disposed within the container and pivoted to the upper portion of the wall thereof 45 and is adapted to be reciprocated at intervals to break up any collection of undissolved bi-carbonate of soda in the container. Said scraper has a shaft 61 which extends outwardly through the wall of and beyond 50 the container and the shell 19 and terminates in an arm 62. Depending pull chains 63 and 64, are secured to said arm and extend in opposite directions and over pulleys 65 pivotally carried by the shell 19 55 and form manually-engageable means by which the scraper may be reciprocated.

The modification illustrated in Fig. 9 is adapted for rooms not subjected to freezing temperatures; and the outer shell 19 is consequently omitted. The pipe 50 is, in this case, contained entirely within the container and the nipple 51 thereof extends through and is sealed in the bottom of the 60 container in an obvious manner.

It is obvious that the invention may be

embodied in further modified structures without departing from the spirit thereof.

I claim:

1. An automatic, self-contained, fire extinguisher having a container for fire-extinguishing fluid formed with a neck, an externally-carried spraying device in communication with the interior of said container, a plug removably secured in the neck of said container, an inverted, normally-sealed, acid bottle held in said container beneath said plug, spring-pressed, bottle-unsealing means slidably extended through said plug into said container, and temperature-responsive means disposed above said plug arranged normally to restrain said spring-pressed means from operation. 70

2. An automatic, self-contained, fire extinguisher having a container for fire-extinguishing fluid formed with a neck, an externally-carried spraying device in communication with the interior of said container, a plug removably secured in the neck of said container, a bottle-holder supported within said container beneath said neck, an inverted acid bottle removably carried by said holder, acid-release means slidably extended through said plug into said container, an acid-bottle stopper carried by said means arranged normally to seal said acid bottle, a spring carried by said release means above said plug arranged to move said means downward and withdraw the stopper from the bottle, and a fusible link extended between said plug and release means to hold said release means 90 from operation. 95

3. An automatic, self-contained, fire extinguisher having a container for fire-extinguishing fluid formed with an internally-screw-threaded neck having an internal annular flange, an acid-bottle holder having a ring received on said flange, an externally-screw-threaded plug received in said neck against the ring of said bottle holder, said bottle holder having means removably to hold an acid bottle therein, an acid bottle received removably in inverted position in said holder, a rod slidably extended through an aperture in said plug having two branches within said container arranged on opposite sides of said bottle holder, an acid bottle stopper secured removably to said arms, said stopper normally arranged to seal said bottle, a standard carried by and above said plug in which said rod is slidably received, a compression spring carried by said rod beneath and in engagement with said standard arranged to force said rod downward and withdraw the stopper from the acid bottle, a fusible link removably extended between said standard and rod arranged normally to restrain said rod against the pressure of said spring, and an externally-carried spraying device in communication with the interior of 105 110 115 120

said container. 130

4. An automatic, self-contained, fire extinguisher having a container for fire extinguishing fluid, an externally-carried spraying device in communication with the interior of said container, temperature-controlled means including a rod slidably extended through an aperture in said container to effect a generation of gaseous pressure within said container, temperature-respon-

sive means externally-carried by said casing 10 arranged to effect a movement of said rod in the operation of said casing, and means carried by said rod arranged to be moved downwardly with said rod to seal said aperture. 15

In testimony whereof, I have signed my name to this specification.

MICHAEL F. HAYES.
